UNITED STATES PATENT OFFICE.

ALONZO T. ADAMS AND JOSEPH DAIN, OF MOLINE, ILLINOIS, ASSIGNEES TO MARSEILLES COMPANY, OF EAST MOLINE, ILLINOIS, A CORPORATION OF ILLINOIS.

GRAIN-ELEVATOR.

1,161,758.

Specification of Letters Patent.

Patented Nov. 23, 1915.

Application filed February 10, 1913. Serial No. 747,491.

To all whom it may concern:

Be it known that we, ALONZO T. ADAMS and JOSEPH DAIN, citizens of the United States, residing at Moline, in the county of 5 Rock Island and State of Illinois, have invented certain new and useful Improvements in Grain-Elevators, of which the following is a specification, reference being had therein to the accompanying drawing.

10 Our invention relates to that class of mechanical structures comprising portable wagon-dumps and elevators employed to remove a load from a wagon and deposit it in some other receptacle, and it consists of 15 a novel and economical arrangement and operation of the various parts as will be more clearly described and claimed hereinafter.

Referring to the drawings in which similar numerals indicate identical parts—Figure 1 is a perspective view. Fig. 2 is a plan of the receiver and part of the elevator. Fig. 3 is a side elevation of Fig. 2, and Fig. 4 is a detail section.

In a structure of this description, power 25 is conveyed to the dumping and elevating mechanism through a power-shaft 1, any suitable power being employed. The dumping apparatus is of an ordinary type, consisting of a frame 2, from which is suspended a vertically movable bar 3 having suspended therefrom loops 4 adapted to engage with the front end of a wagon to raise it so that the load will be deposited in a receiver 5 at the foot of an elevator 6, and 30 forming part thereof. The bar 3 is raised or lowered by means of a cable 7 on a drum 8, the latter operated from the power-shaft 1 by means of intervening gearing in a manner well known in the art.

40 The receiver 5 is located so that any wagon being dumped will deposit the load therein, the latter falling upon a conveyer 9, at the bottom of the receiver 5, moving toward the elevator 6 and carrying thereto the material received from the wagon. The conveyer 9 consists of sprocket chains 10 and 45 11 engaging with sprockets 12, and having secured to them at suitable intervals blades 14. The sprockets 12 are idlers and revolve on a shaft having bearings in the outer end of the receiver 5. The sprockets 13 are secured on a tubular shaft 15 which is revolvable in bearings 16 and 17 on the elevator end of the receiver 5. On an end of the tubular 50 shaft 15 is a sprocket 18 carrying a chain 19

which engages with a sprocket 20 secured on a tubular shaft 21 and receiving motion from the power-shaft 1 as will be explained. The tubular shaft 21 revolves in roller bearings 22 and 23 forming part of brackets 24 and 25 secured to the sides of the elevator box 26.

The power-shaft 1 is preferably composed of three sections, *a*, *b*, and *c*; the central section *b* is journaled in the tubular shaft 21, 65 and has upon one end a member 27 of a clutch which is free to move longitudinally thereon but which revolves with the power shaft section *c*, being held in engagement therewith by a spline 28 seated in the section *b*; the section *b* is connected to the section *a* by a universal coupling 29, the latter section receiving motion from the power utilized to operate the machine. A collar 30 encircles the clutch member 27, the latter 70 revolving freely therein; to the elevator box 26 is attached a laterally extending arm 31 to which is pivoted a vertical lever 32 which engages with the ring 30, so that a movement of the lever 32 toward the receiver 5 75 will engage the clutch member 27 with a clutch member 33 on the face of the sprocket 20 to operate the conveyer 10 in the receiver 5 through the chain 19 and sprocket 18, and at the same time imparting motion to the 80 conveyer 34 in the box 26 forming the elevator, the latter conveyer being similar in construction to the conveyer 9, and carried on sprockets 35 and 36 secured to the tubular shaft 21 and revolving therewith. 85

The power-shaft section *c* is coupled to a clutch member 37 which is loosely mounted on the power-shaft section *b*, and power to operate the dumping mechanism through the section *c* is conveyed to the latter by 90 moving the lever 32 away from the receiver 5 until the clutch members 27 and 37 are in engagement. Normally the clutch member 27 is out of engagement with the members 33 and 37 as shown in Fig. 4, so that the 95 conveying and elevating mechanism can be operated independently of the dumping mechanism, or both may remain idle while the sections *a* and *b* of the power-shaft 1 are revolving.

On each side of the receiver 5 is hinged a door 38 and 39 and adapted to fall into the position shown in dotted lines in Fig. 4 forming a hopper when the load from a wagon is dumped into the receiver, the limit 110

of the door movement being regulated by suitable hook arms attached thereto and adapted to catch on the receiver in a well known manner.

- 5 To automatically start the operation of the conveying mechanism a rod 40 is rockable in bearings on a side of the receiver 5, one end 41 of said rod being bent, as shown in Fig. 3, to present a greater bearing surface 10 face against the door 38; the other end of the rod 40 is bent outwardly and upwardly forming a crank arm 42 in which is a vertical slot 43; connected to the crank-pin 42 in the slot 43 is a rod 44 which projects 15 through the tubular shaft 15 and is attached to the lever 32; a coiled spring 45 on the rod 44, and interposed between the lever 32 and sprocket 18, tends to keep the door 38 in a closed position; it will be readily apparent 20 that the pressure of the material dumped into the receiver will cause the door 38 to drop, rocking the rod 40 and actuating the rod 44 to move the lever 32 toward the receiver 5 and engaging the clutch members 25 27 and 33 so that revolution of the power-shaft sections *a* and *b* will impart motion to the conveying and elevating mechanism; when the pressure on the door 38 is removed the expansion of the spring 45 will close 30 said door by rocking the rod 40 to its normal position, and at the same time the clutch members 27 and 33 will be disengaged and the conveying and elevating mechanism will stop.

35 What we claim is—

1. The combination with an elevator, of power actuated means for operating said elevator but normally out of engagement therewith, a lever adapted to be manually 40 operated to connect the elevator with the power actuating means, and means to automatically operate said lever to connect the elevator with the power actuating means.

2. The combination with an elevator, of power actuated means for operating said elevator but normally out of engagement therewith, a receiver forming part of the elevator and having a door thereon adapted to swing outwardly, and means operated by 50 the outward swing of said door to connect said elevator with said power actuating means.

Copies of this patent may be obtained for five cents each, by addressing the "Commissioner of Patents, Washington, D. C."

3. The combination with an elevator, of power actuated means for operating said elevator but normally out of engagement therewith, a receiver forming part of the elevator and having a door thereon adapted to swing outwardly, a lever operable to connect the elevator with the power actuating means, and a rod engaging with said door and connected to said lever to actuate the latter by the downward swing of the door to connect said elevator with the power actuating means.

4. The combination with an elevator, of power actuated means for operating said elevator but normally out of engagement therewith, a receiver forming part of said elevator and having a door thereon adapted to swing outwardly, a lever operable to connect the elevator with the power actuating means, a rod engaging with said door and extending along the receiver to which it is rockably secured, a crank-arm on said rod, a rod extending transversely of said receiver and connected to said crank-arm and said lever to actuate the latter by the downward swing of the door to connect the elevator with the power actuating means.

5. The combination with an elevator, of power actuated means to operate said elevator, comprising a tubular shaft, means connecting said shaft with the elevator, a shaft within the tubular shaft and connected with a source of power, and means automatically operable to connect said shafts for simultaneous movement.

6. The combination with an elevator, of power actuated means to operate said elevator, comprising a tubular shaft connected with the elevator, a shaft within the tubular shaft and connected with a source of power, means manually operable to connect said shafts for simultaneous movement, and means to automatically actuate said manually operable means.

In testimony whereof we affix our signatures, in presence of two witnesses.

ALONZO T. ADAMS.
JOSEPH DAIN.

Witnesses:

BERTHA A. MAURER,
W. G. DUFFIELD.

It is hereby certified that in Letters Patent No. 1,161,758, granted November 23, 1915, upon the application of Alonzo T. Adams and Joseph Dain, of Moline, Illinois, for an improvement in "Grain-Elevators," an error appears in the printed specification requiring correction as follows: Page 2, line 13, for the compound word "crank-pin" read *crank-arm*; and that the said Letters Patent should be read with this correction therein that the same may conform to the record of the case in the Patent Office.

Signed and sealed this 18th day of January, A. D., 1916.

[SEAL.]

J. T. NEWTON,

Cl. 193—14.

Acting Commissioner of Patents.
